UNITED STATES PATENT OFFICE.

RICHARD ERNST SCHLETER, OF PHILADELPHIA, PENNSYLVANIA.

FULL-FASHIONED CLOCKED HOSIERY AND METHOD OF MAKING SAME.

Application filed January 6, 1923. Serial No. 611,193.

To all whom it may concern:

Be it known that I, RICHARD ERNST SCHLETER, a citizen of the Republic of Germany (naturalization papers applied for), ⁵ residing at the city of Philadelphia, county of Philadelphia, and State of Pennsylvania, have invented certain new and useful Improved Full-Fashioned Clocked Hosiery and Methods of Making Same, of which the following is a specification.

This invention, generally stated, has relation to hosiery of full fashioned type and has more particular relation to fashioning clocks thereon.

15 Commercially considered, two types of clocked hosiery are in use. In one type clocks are of open work, termed clock-lace, and stockings of this type being relatively fragile are not suited for all occasions or 20 every-day use and furthermore are comparatively expensive. The other type comprises hosiery in which clocks are embroidered thereon. While this type is best suited for every-day use practice dictates, that, the action of needles laying-on the embroidery yarn serves to so weaken the stocking-web as to have a deleterious effect thereon. The 25 embroidering operation also serves to increase manufacturing costs.

30 The leading object of the present invention is to overcome the above described, disadvantageous features and provide full fashioned hosiery with clocks knitted in with the stocking-web by means of re-inforcing thread, whereby, not only is the stocking-web adjacent said clocks strengthened and the cost of production reduced, thus 35 providing hosiery suitable for every-day use, but, in addition, hosiery is provided possessed of unique, structural characteristics 40 presenting an ornamental and distinctive appearance, rendering such hosiery suitable for wear upon special occasions also. A further object of the present invention is to 45 provide fine, chiffon silk hosiery with clocks in such manner, that, while the ankle portion thereof is re-inforced by such clocks the latter are not detrimental to the appearance 50 of the stocking, but, upon the contrary enhance its appearance. A still further object of the present invention is to knit into the ankle portion of a stocking-web, simultaneously with the formation of clocks, re-inforcing thread in alignment with the 55 heel-parts but spaced from the clocks where-

by a re-inforced, rear ankle portion is provided above the heel of a stocking.

With these and other objects in view, the invention consists of the improvements hereinafter described and finally claimed. ⁶⁰

The nature, characteristic features and scope of the invention will be more fully understood from the following description, taken in connection with the accompanying drawings forming part hereof, and in ⁶⁵ which:—

Fig. 1, is a fragmentary view of a stocking-web fabricated in accordance with the present invention.

Fig. 2, is a view in side elevation of a ⁷⁰ completed stocking.

Fig. 3, is a fragmentary view of a stocking-web exposing both sides of a clock, and

Fig. 4, is a fragmentary view of another ⁷⁵ form of stocking-web fabricated in accordance with the present invention.

For the purpose of illustrating my invention I have shown in the accompanying drawings two forms thereof which are at present preferred by me, since the same have ⁸⁰ been found in practice to give satisfactory and reliable results, although it is to be understood that the various instrumentalities of which my invention consists can be variously arranged and organized and that my invention is not limited to the precise arrangement and organization of the instrumentalities as herein shown and described. ⁸⁵

The web of hosiery embodying features of the present invention is knit upon a ⁹⁰ straight knitting machine equipped with mechanism capable of co-acting with respect to the web-forming needles to provide reinforcements having zig-zag-like lines inclined to the wales and courses of the web. ⁹⁵

An example of such stocking re-inforcement is disclosed in Letters Patent granted to me under date of September 19, 1916, and numbered 1,198,482. In manufacture, the stocking-web, which has selvage edges, is knit in a well understood manner to that portion of the leg at which the narrowing operation takes place. In the drawings the stocking-web is designated 10 and the narrowing leg portion is designated 11—11. ¹⁰⁰ At or about the time narrowing of the leg portion is commenced, additional or re-inforcing thread is presented to certain of the web-forming needles to effect formation of a clock or clocks 12. During formation ¹⁰⁵ 110

of a clock or clocks it is to be understood, that, fabrication of the stocking-web, including the re-inforced heel portions 13—14, takes place in the usual and well understood manner of making full fashioned hosiery. The additional or re-inforcing thread is supplied to the web-forming needles so that zig-zag-like lines inclined to the wales and courses of the web are produced to effect the contour of a clock or clocks. Obviously, depending upon the contour of a clock or clocks desired, the feeding of additional thread varies. It is to be understood also, that, the clock or clocks may extend above or below the parts 11—11 of the web. In practice I commence the formation of the clock or clocks midway of the narrowing portion of the web. Obviously but one clock may be formed upon a stocking-web if desired, although in practice two are provided. As the steps of formation of two clocks are mere duplication the following description, for illustrative purposes, will be restricted to the fabrication of single clocked stocking-web.

Referring now more particularly to the form shown in Figs. 1, 2 and 3, a description of the method of formation will now be given. At or about the time the narrowing of the stocking-web 10 takes place one or more of the web-forming needles are provided with additional or re-inforcing thread to form the top 15 of a clock. At predetermined intervals, thereafter, additional needles have fed thereto said thread to provide a re-inforced portion of gradually increasing width the outline or contour of which is comprised of zig-zag-like lines 16—16. The re-inforcing thread at predetermined intervals is now withheld from the stocking-web forming needles to form the lines 17—17 thus completing a conventional, leaf-like figure 18. From the bottom of this figure 18 there is extended downwardly, in a vertical manner, a portion 19 formed by one or more web-forming needles knitting re-enforcing thread into the web 10. At a predetermined place said portion 19 may have added thereto a small design, as a cross 20, formed by supplying, at predetermined intervals, additional needles with re-inforcing thread and then withholding said thread at similar intervals. Upon completion of portion 19, additional needles are provided with re-inforcing thread to provide widened part 21. At a predetermined place part 21 is also widened to provide part 22 which latter part, in turn, is widened at a predetermined place to provide part 23 which extends down to a heel part. The combined parts 19, 21, 22 and 23 form a vertical, stem-like figure gradually increasing in width upon each side of a medial line extending vertically therethrough. The outline or contour of such stem-like figure is formed by zig-zag-like lines although not as pronounced as in the leaf-shaped figure. At or about the time that the formation of part 23 is commenced a group of web-forming needles, spaced from those forming a clock, 70 are provided with re-inforcing thread and knit into the web, simultaneously with the formation of the balance of part 23, a re-inforced part 24 which extends laterally from a selvage edge of the stocking-web toward a clock. The part 24 is at the rear of the ankle, is above the heel and in alignment therewith and is spaced from a clock. This part 24 is positioned to resist wear at or near the heel in the rear thereof. This provides a 80 useful adjunct to a stocking, is not detrimental to its appearance because it blends with the particular type of clocks employed and is inexpensive in that it may be fabricated simultaneously with a clock. Upon 85 completion of part 23 of the clock and the part 24 at the stocking rear, the clock is finished by withholding re-inforcing thread from certain of the needles and permitting others to knit re-inforcing thread in a direction toward the stocking toe for a pre-determined distance as indicated at 23'. This part is spaced from the re-inforced foot portion and forms a finish for the lower portion of a clock. Simultaneously with the 90 formation of part 23', certain of the needles which have formed clock part 23 and heel part 24 and those needles forming the part there-between are supplied with re-inforcing thread to effect formation of a conventional 100 re-inforced heel part. A conventional foot is then attached to the stocking-web in the usual manner.

A description will now be given of the formation of a stocking-web as disclosed in Fig. 4. At or about the time the narrowing of the stocking-web takes place one or more of the web-forming needles are provided with additional or re-inforcing thread to form the top 25 of a clock. At predetermined intervals, thereafter, additional needles have fed thereto said thread thus providing a re-inforced portion of gradually increasing width the outline or contour of which is comprised of zig-zag-like lines 110 26—26. The re-inforcing thread, at predetermined intervals, is now held free of certain of the web-forming needles thus providing a re-inforced portion of gradually 115 decreasing width, the outline or contour of which is comprised of zig-zag-like lines 27—27. Thus a relatively diamond-shaped figure 27' is produced. From the bottom of this figure 27' there is extended downwardly, in a vertical manner, a portion 28 formed by one or more web-forming needles being supplied with re-inforcing thread. At a predetermined place such part 28 may be widened as at 29 by supplying additional 120 needles, at least one upon each side of the 125 130

group which has formed part 28, with re-inforcing thread. At a predetermined place part 29 may be also widened, in a manner similar to that above described, to form 5 part 30. This part 30 may in turn, at a predetermined place, be also widened for a desired distance to form part 31. The combined parts 28 to 31, inclusive, form a vertical, stem-like figure gradually increasing 10 in width upon each side of a medial line extending vertically therethrough. The outline or contour of such stem-like figure is formed by zig-zag-like lines although not as pronounced as in the diamond shaped 15 figure 27'. The stem-like portion above described is now appreciably widened along zig-zag-like lines 32-33 by supplying additional web-forming needles with the re-inforcing thread. The above described, reinforced 20 part forms a clock spaced from the selvage edge of the web. The zig-zag-like line 32 is carried further down the ankle-portion of the web than is the line 33 and at a predetermined place all of the web-forming 25 needles between a selvage edge and a clock are supplied with additional thread to provide a re-inforced heel part. The stocking is now finished in the usual manner it being understood that the heel re-inforcement is 30 a continuation of the clock as fabricated.

The above described methods of fabrication provide neat, attractive and comparatively inexpensive hosiery. Further fine chiffon silk may be employed because the 35 clocks, being formed simultaneously with and knitted directly into the stocking-web, act as re-inforced parts and provide for stability. A clocked stocking-web as above described and formed, is a reversible fabric, 40 the clocks appearing upon opposite faces of a web as clearly shown in Fig. 3. While the above description and drawings have been restricted to two designs of clocks, for 45 illustrative purposes, it will be understood that varied styles of clocks may be effected by providing various combinations of web-forming needles with additional or re-inforcing thread.

Clocked hosiery as above described may 50 be fashioned from silk or other thread, for instance white silk, and then "dipped" for instance in black dye to provide a stocking in which the web and clock are of the same color. In case it is desired to have a stocking-web and clock of contrasting colors the 55 same may be accomplished either according to "dipping" procedure or to "ingrain" system of formation. In the former case, assuming for the purpose of illustration that 60 a green clock is desired upon a black stocking, the web is knit from undyed silk or other thread as usual, but, the re-inforcing thread, as introduced to form a clock, has been colored green with specially prepared 65 dye to resist accepting dye of any other

color. Thus when the undyed stocking-web is treated with black dye, the green clock does not accept the black dye but retains its original color. In case of "ingrain" system of formation, the stocking-web is knit 70 from thread of one color and the re-inforcing thread used in forming a clock is of another color. For example the thread forming the web may have previously been dyed black and the re-inforcing thread may have 75 been dyed green. If it be desired to have a white stocking-web with a colored clock obviously it is only necessary to dye the re-inforcing thread previous to introduction to the web-forming needles. 80

In practice a flat knitting machine is provided with an attachment for operating at predetermined intervals those thread carriers upon the machine which supply the web-forming needles with re-inforcing 85 thread.

It will now be apparent that I have devised novel and useful constructions which embody the features of advantage enumerated as desirable in the statement of the 90 invention and the above description, and while I have in the present instance shown and described the preferred embodiments thereof which have been found in practice to give satisfactory and reliable results, it 95 is to be understood that the same are susceptible of modification in various particulars without departing from the spirit or scope of the invention or sacrificing any of its advantages. 100

What I claim is:—

1. The herein described method of manufacturing full fashioned clocked hosiery which consists in knitting directly into the stocking-web in spaced relation from the opposite edges thereof; and simultaneously with formation of said stocking web re-inforcing thread in successive clock-forming courses, said courses defining zig-zag-like lines substantially inclined to the wales and courses of said web and continuing knitting of re-inforcing thread to form re-inforced heel-portions which are continuations in part of said clocks. 105

2. The herein described method of manufacturing full fashioned clocked hosiery which consists in knitting a stocking-web until the usual narrowing operation takes place, substantially at which time re-inforcing thread is provided selected web-forming needles spaced from the opposite edges of the web for introducing the re-inforcing thread into the web in successive clock forming courses, the opposed ends of the courses defining zig-zag-like lines substantially inclined to the wales and courses of said web, which operation continues until the heel portion of the web is reached at which time re-inforcing thread is provided additional 110 needles to form re-inforced heel-portions 115

which are continuations in part of said clocks.

3. The herein described method of manufacturing full fashioned clocked hosiery which consists in knitting directly into the stocking-web in spaced relation from the opposite edges thereof; and simultaneously with formation of said stocking-web, re-inforcing thread in successive clock-forming courses, the opposed ends of said courses defining zig-zag-like lines substantially inclined to the wales and courses of said web and before clock completion simultaneously forming in conjunction therewith re-inforced rear ankle portions spaced from the clocks and thereafter forming a re-inforced heel the same being a continuation in part of said clocks and re-inforced ankle parts.

4. As a new article of manufacture a full fashioned clocked stocking, the opposed clocks being formed of successive courses of re-inforcing thread knitted directly into the stocking-web in spaced relation from the stocking rear seam; and simultaneously with

formation of said stocking-web, the opposed ends of which courses define zig-zag-like lines substantially inclined to the wales and courses of said web, said stocking having re-inforced heel portions which are continuations in part of said clocks.

5. As a new article of manufacture a full fashioned clocked stocking, the opposed clocks being formed of successive courses of re-inforcing thread knitted directly into the stocking-web in spaced relation from the stocking rear seam; and simultaneously with formation of said stocking-web the opposed ends of which courses define a zig-zag-like line substantially inclined to the wales and courses of said web said stocking having re-inforced rear ankle portions spaced from the clocks, said stocking having re-inforced heel portions which are continuations in part of said clocks and reinforced ankle parts.

In testimony whereof, I have hereunto signed my name.

RICHARD ERNST SCHLETTNER.
